UNITED STATES PATENT OFFICE.

CHARLES C. BAILEY, OF WELLSBURG, NEW YORK.

SPRING CUSHION-SUPPORT FOR CARRIAGE-SEAT BACKS.

SPECIFICATION forming part of Letters Patent No. 239,694, dated April 5, 1881.

Application filed September 23, 1880. (Model.)

To all whom it may concern:

Be it known that I, CHARLES C. BAILEY, of Wellsburg, Chemung county, New York, have invented a new and useful Improvement in 5 Spring Cushion-Supports for Carriage-Seat Backs, of which the following is a specification.

Figure 1 is a perspective view of the improvement, shown as applied to a carriage-seat back. Fig. 2 is a vertical section, showing the 10 arrangement of the spiral springs; and Fig. 3 is a horizontal section, showing the arrangement of the spiral springs.

Similar letters of reference indicate corresponding parts.

15 The object of this invention is to furnish spring-supports for the cushions of carriage-seat backs between the seat-backs and the lazy-backs, to hold the cushion out against the backs of persons riding in the seats and prevent the cushions from sagging, and which shall be so constructed that they can be attached to any seat-backs.

The invention consists in constructing a 20 spring cushion-support for carriage-seat backs of a spring-frame, having a dovetailed or **T** groove in its central bar, spiral springs to be interposed between the spring-frame and the rods that support the lazy-back, plates having studs for connecting the spiral springs with 25 the spring-frame, and plates having grooved studs and clamps for connecting the spiral springs with the rods that support the lazy-back, whereby the back-cushion will be supported and held out against the backs of the 30 persons riding in the seat, as will be herein-after fully described.

A represents the bottom, B the ends, and C the back, of a carriage-seat.

D is the lazy-back, which is supported by 40 the rods E and the arms or braces F. The upper ends of the rods E are attached to the lazy-back D, and their lower ends are attached to the seat-back C and the bottom A. The rear ends of the arms or braces F are attached 45 to the ends of the lazy-back D. The arms F are bent downward, forward and downward, and their forward ends are attached to the ends B and bottom A of the seat. As thus far described there is nothing new in the construction.

50 G is a spring-frame, formed by attaching three horizontal bars or springs to a number

of upright bars or springs, as shown in Fig. 1. The spring-frame G is bent into any desired form, as the style of the carriage-seat may require. The upper ends of some or all of the upright bars or springs of the spring-frame G project, and are attached to the lazy-back D. The upper and lower edges of the central horizontal bar of the spring-frame G are bent 55 rearward and inward to form a dovetailed or **T** groove to receive the plates H, upon the centers of which are formed, or to them are attached, studs I, to receive the smaller forward ends of the tapered or conical spiral 60 springs J. The forward ends of the spiral springs J, after being coiled around the studs I, are passed through holes in the plates H, and are riveted to the said plates. The rear or larger ends of the spiral springs J are placed 65 in grooves in the studs K, formed upon or attached to the plates L, upon the rear sides of which are formed stationary jaws M, having half-round or half-diamond-shaped grooves 70 formed in their faces to receive the rods E, 75 that support the lazy-back D, whether the rods E be round or oval.

To the faces of the stationary jaws M are fitted the faces of the movable jaws N, which have half-round grooves formed in their said 80 faces to fit upon the rods E. The jaws M N are drawn together, to clamp the rods E, by the screws O, which pass through holes in the outer ends of one of the said jaws and screw into screw-holes in the outer ends of the other 85 jaws, as shown in Figs. 2 and 3. After the clamps M N O have been adjusted upon and secured to the rods E, and the plates and studs H I have been adjusted in the groove of the central bar of the spring-frame G, the bent or 90 flanged edges of the said bar are bent inward or dented at the sides of the plates H, to keep the said plates H, and with them the ends of the springs J, in place.

With this construction the spring-frame G 95 can be secured to the seat-back, whether the rods E be straight or bent, and whatever be the style of the seat.

With this improvement the upholstering or back-cushion will be supported between the 100 seat-back C and the lazy-back D and prevented from being pressed into the space between the said parts. The improvement also presses the cushion against and supports the

backs of the persons sitting in the seat, and greatly increases their comfort in riding.

Having thus described my invention, I claim as new and desire to secure by Letters Patent—

1. A spring cushion-support for carriage-seat backs, constructed substantially as herein shown and described, consisting of the spring-frame G, having a dovetailed or T groove in its central bar, the plates H, having studs I, the spiral springs J, the plates L, having grooved studs K, and clamps M N O, to adapt the support to be applied to the back of a carriage-seat, as set forth.

2. The combination, with the lazy-back D and the rods E, that connect the lazy-back with the back of a carriage-seat, of the spring-frame G, having a dovetailed or T groove in

its central bar, the plates H, having studs I, the spiral springs J, the plates L, having grooved studs K, and clamps M N O, substantially as herein shown and described.

3. The combination, with the spring-frame G, attached at its upper edge to the lazy-back D of a carriage-seat, and the rods E, that support the lazy-back D, of the spiral springs J, connected at their ends with the said spring-frame and rods, substantially as herein shown and described, whereby the back-cushion of the carriage-seat is held out against the backs of persons riding upon the seat, as set forth.

CHARLES CLAUDIUS BAILEY.
